UNITED STATES PATENT OFFICE.

GEORGE W. WHITE, OF NEW YORK, N. Y., ASSIGNOR TO P. & F. CORBIN, OF NEW BRITAIN, CONNECTICUT.

DESIGN FOR DOOR-KNOBS.

Specification forming part of Design No. 6,623, dated April 29, 1873; application filed April 18, 1873.

To all whom it may concern:

Be it known that I, GEORGE W. WHITE, of the city and State of New York, have invented a Design for Door-Knobs, of which the following is a specification:

In the accompanying photographic illustration, Figure 1 represents the knob and plate or escutcheon by a perspective view. Fig. 2 is a face view of the knob; and Fig. 3 is an elevation of the plate or escutcheon for said knob.

Around the periphery of the knob is an ornamental band, *a*, and in the middle of the knob is a circular band, *b*, inclosing a Gothic rosette ornament. Around this band *b* are reversed cuspidated arches and trefoil ornaments, as represented. The plate or escutcheon is ornamented with cuspidated arches reversed, as at *h*, and above the central portion of this

escutcheon is the ornamental plate *k*, with leaflets and scrolls. The downward projections *l l* of this escutcheon are ornamented with the leaflets and scrolls, as represented.

The design of the escutcheon is especially adapted to accompany the knob, but either ornamentation may be used without the other.

I claim as my invention—

The design of the ornamentation upon the knob, and the design of the ornamentation upon the escutcheon, substantially as described and represented.

Signed by me this 15th day of April, A. D. 1873.

GEO. W. WHITE.
